UNITED STATES PATENT OFFICE.

GUSTAVE PÉREIRE, OF PARIS, FRANCE.

ART OF MANIFOLDING.

1,292,868.

Specification of Letters Patent. Patented Jan. 28, 1919.

Application filed March 20, 1914. Serial No. 826,038.

To all whom it may concern:

Be it known that I, GUSTAVE PÉREIRE, a citizen of the Republic of France, residing at 69 Rue de la Victoire, Paris, France, have 5 invented a new and useful Improvement in the Art of Manifolding, which improvement is fully set forth in the following specification.

Very complete studies undertaken during 10 about the last fifteen years on the book-keeping of railways, important industries, assurance companies, savings banks, banks and any kind of business generally, such as customs and indirect taxes, have shown the 15 necessity which existed of simplifying as far as possible the system of preparing the documents for book-keeping (way bills for sending goods by passenger and luggage train, insurance policies, etc.,) and of realizing a 20 more complete agreement between the written accounts in the different services, sections or railways and the work of auditing carried out by the various controlling departments, with the object of avoiding the copying 25 of entries, thus eliminating a source of error.

The object of the present invention is to facilitate the work of concurrently preparing a number of tabulated sheets at the different controlling or checking central offices of the tabulating department economically and with a complete elimination of errors. The invention comprises as its essential features, first, the simultaneous perforation of a superimposed pile of sheets with 30 perforations spaced according to the horizontal spacing of markings on the topmost sheet corresponding to certain required data; second, the setting up of type to print a line 35 of tabulation on each sheet, the type being spaced according to the spacing of the perforations; third, printing from the line of type so set up on each sheet; and fourth, attaching strips bearing such printed lines to 40 respective assembling sheets at the central controlling stations. By this procedure, the manifolding of the tabulated strips is not only effected economically, but errors are 45 eliminated, and all the assembled sheets at the various central stations are absolute and correct copies of each other, while the tabulated figures and signs representing the desired data will be in perfect register.

It has already been proposed with this object (see the French Patent No. 405,726, of 55 the 4th of August, 1909), to arrange headed tables on which were entered and fixed one under the other in any suitable way printed gummed bands for the accounts in question and containing the necessary indications in 60 such a way as to facilitate addition. The pieces had been previously prepared to the desired number of copies and the addition of the items could then be easily affected.

The object of this invention is to facilitate 65 the work of preparing these account sheets in such a manner as to be able quickly to obtain, economically and without the possibility of errors, the required number of 70 copies and the well known system is used of the American printing machine called "Monotype" and currently employed actually in a number of printing establishments.

In this machine there are two series of operations:

(a) one manual for producing a registering strip in which are made perforations corresponding to the characters, spaces, signs to be reproduced, or to the operations to be effected by the automatic composing machine;

(b) the other automatic, regulated by means of this registering strip which allows of translating the signs which have been perforated into their proper lines of the 85 typographic text or of producing the latter.

The nature of the invention will be explained in connection with the accompanying drawings, in which:

Figure 1 shows a portion of a perforated 90 band for a monotype machine;

Fig. 2 represents diagrammatically the framework of a matrix carrier;

Fig. 3 shows a portion of a typical way-bill marked in accordance with the invention;

Fig. 4 illustrates in plan apparatus suitable for carrying out one form of the present method;

Fig. 5 is a detail view of part of the apparatus of Fig. 4;

Figs. 6 and 7 are top and bottom perspective views, respectively, of a printing device;

Fig. 8 embodies top and bottom perspective views of a single type;

Figs. 9 and 10 are top and bottom perspective views, respectively, of a type bar intended for use in another form of apparatus;

5 Figs. 11 and 12 are top and bottom plan views, respectively, of a frame carrying type bars like those shown in Figs. 9 and 10;

Fig. 13 is a perspective view in side elevation of still another form of apparatus with 10 in the invention;

Fig. 14 is a partial plan view of the same; and

Fig. 15 is a diagrammatic plan view of another form of apparatus.

15 For the first operation a key board is employed, a kind of machine for special writing usually comprising 225 keys which represent as many characters, signs or symbols, and which control through suitable mechanism punches which perforate the registering strip.

For the second operation the type casting machine is used, a machine for casting or founding the characters, comprising 225 25 matrices which correspond to the characters, signs or symbols.

In the case of matrices for founding type, the matrices are arranged in fifteen columns and fifteen rows; in the machine for composing the strip the punches are arranged in line and divided into two groups each column of matrices being represented by a punch in one of the two groups and each row of matrices being represented by a punch in 35 the other group.

It may be observed that out of the 225 40 keys 196 of them cause in the band of paper two perforations for each letter, number or sign as is seen in Fig. 1 of the accompanying drawing which shows a portion of perforated band for a monotype machine.

The 29 other keys only have one perforation for a letter, number or sign.

In Fig. 2 of the drawing which shows 45 diagrammatically the framework of the monotype matrix carrier there are shown by white circles *a* the matrices corresponding to two perforations the black matrices *b* only corresponding to one.

50 It is proposed according to this invention to utilize this feature of the monotype process for the preparation of account sheets, way bills or other similar documents, for which are needed numbers 0 to 9 and signs, 55 altogether not more than fourteen characters. For these fourteen elements which are necessary and sufficient for all cases there is adopted one of the two lines in question of the matrix frame of the monotype machine

60 giving fifteen intervals and only necessitating a single perforation, which will be the more suitable for the needs of the work.

The account sheet (for greater clearness the case will be taken of a way bill for for-

warding goods) is specially prepared in 65 columns with vertical and horizontal lines having preferably in faint ink an indication of the number to be perforated as shown in Fig. 3 which shows a part of a model way bill. The horizontal lines of the bill will 70 be placed according to the spaces of the monotype machine the bill itself being of the same width as the strip used on the monotype machine if it is not desired to make any actual change in the type casting 75 but any modifications may be introduced to make larger bills as will be explained hereinafter.

On the left of Fig. 3 are shown the relative positions of the perforations which the 80 punches produce on the band corresponding to the characters of the selected lines on the key board of the machine. The characters chosen will be:—white (or a spaced left blank, shown in the drawing by a square): 85

1 2 3 4 5 6 7 8 9 0 . ,

In order to fill up the bill it is only necessary to perforate it in any suitable manner as shown hereinafter as an example, in such a way as to register in each column the desired details but for greater security in order to avoid any chance of error the numbers and signs of the desired details are marked or impressed at the same time on a space reserved for them in each column: 33 in the 95 first column, 2298 in the second, etc. The principle of perforating the sheet is as follows:

Writing or marking of a number or a sign and a corresponding perforation confirming 100 the indication given by this number or sign.

When once the bill is obtained either using a modified or rather simplified keyboard because only a very small number of keys is used, it may be by one of the processes indicated hereinafter as an example, it will be easy to obtain the perforated signs of the bill for reproducing them on the monotype machine as strips are usually reproduced on a monotype machine. It will be understood 110 the monotype machine can advantageously be simplified in its construction to suit this new important application. As it will be desired, for greater precision and certainty to make in the paper of the bills to be reproduced holes of greater diameter than those actually made on a monotype machine, and consequently to use wider paper, only slight modifications need be made to the machine to adapt it to suit these requirements. 115

In order to prepare perforated sheets which may be waybills, letter bills, sheets for insurance policies, and in general all kinds of accounts, and which will be sent to the founder, many methods may be employed, 125 the choice of which will depend upon the resources and needs of the stations, sections, or services. But there will never be need to

depart from the fundamental principle already described: the marking or impression of a number or sign and the corresponding perforation confirming the mark given by the number or by the sign.

5 Different methods of preparing the perforated strip will be given as examples:

1st. At first sight the most simple method of perforating and marking the numbers or 10 signs is by hand, which is applicable to small stations for example. The perforations should be made very exactly at the intersection of the horizontal and vertical lines of the bill by means of a punch or other suitable 15 instrument, and will resemble the perforations made by the keyboard of the monotype machine.

2nd. Preferably the apparatus shown in plan in Fig. 4 will be used (Fig. 5 being a 20 detail view), this apparatus comprises a frame *d* on which the waybill is placed; along the short sides of this frame slides a perforated gage *e* which serves to determine exactly the horizontal line to be perforated. 25 An extensible perforator *f* pivoting and free to slide on an axis *g* serves to perforate the bill through one of the holes in the gage.

30 This apparatus allows ten bills to be perforated at once which is necessary in the case of railways.

35 By the aid of a typographic process similar to that used by the blind, it is possible to effect very quickly and easily the marking on these bills of numbers and signs corresponding to the holes which have been perforated.

40 To carry this out it is sufficient to provide a suitable number of small blocks of metal for example having on one face the number or sign forming the printing type, and on the opposite face the similar number or sign, larger and easily visible. With a suitable kind of composing stick, it will be easy to print on the ten sheets which may 45 be already perforated the necessary numbers to render the bill readable.

45 Figs. 6 and 7 of the drawings are top and bottom views of this apparatus, Fig. 8 being a perspective view of a single type.

50 The apparatus consists of a frame 1 with a pressure screw 2 in which are placed side by side a number of type 3. Each type has on one of its faces a printing surface and on the opposite face the corresponding number or sign on a larger scale so as to be 55 readily visible.

55 The line to be printed on the bill is composed by arranging the blocks side by side by means of the large characters. The 60 blanks are filled by leads 3'. Then the screw 2 is turned and after having inked the type by the aid of any suitable means, the bills are printed.

It will be seen that the printing of bills

by the aid of this arrangement will be extremely simple and capable of being done by any one; it will be of particular interest to small railway stations.

65 3rd. More certain methods can be employed equally well; for example the typographic method: the numbers being typographed and the perforations made simultaneously (see Figs. 9 to 12 in which Figs. 9 and 10 are top and bottom perspective views of a bar, Figs. 11 and 12 being plan 70 views of a frame taken from above and below).

75 For this apparatus special type are used formed of bars *h* (Figs. 9 and 10) which are placed side by side in a screw frame *i* in a sufficient number to compose the whole bill. Each bar has on one face a number or letter *j* upon it, and on the other face a type *k* in relief and a perforating rod *l* on a suitable part of the bar. When the bars *h* are assembled in the frame *i* it is firmly compressed, then the type are turned upward (Fig. 11). It is then sufficient to pass an inking roller by hand over the type *k*, place the bill to be printed and perforated and 80 press it onto the plate by means of a press. The type will be printed and the rod *l* will at the same time perforate the paper at the desired place.

85 To effect the work more rapidly and with greater certainty, the apparatus shown in Figs. 13 and 14 can advantageously be employed in which Fig. 13 is a perspective view and Fig. 14 a partial plan view. It consists of a suitable number of identical 90 elements placed next to each other in the same box *m*. Each element is formed of two sectors *n*, *n'* pivoted at *n*, *n'*. A common rack *o* operated by a rod *p* actuates simultaneously these two sectors which are 95 provided for this purpose with teeth *q*, *q'* which engage with the rack. This latter moves at the same time a perforating rod *r* which is thus moved as the end of the operating rod *p* is moved in the grooves *s*, *t* situated in the top of the box *m*. Each sector has on its periphery a certain number of numbers or signs *u*, *u'* in relief, which appear successively in the apertures *v*, *v'* in the top of the box: the numbers or signs on the 100 sector *n* form printing type.

105 In order to use the apparatus each of the connecting rods is moved by hand until the number or sign desired is brought before the aperture *v'*. It is then certain that the 110 elements in question are in their proper places, viz: the number or sign *u* forming a printing type and the perforating rod *r*. When once all the elements are thus adjusted the types are inked, the sheet to be 115 printed and perforated is placed in position, the press is operated, and the work is 120 printed and perforated is placed in position, the press is operated, and the work is 125 done.

4th. It will be understood that these methods of perforating and printing the strips are only given as examples. For instance it is equally possible to use a printing machine having the type in a disk and an operating lever. To effect this it is necessary to provide a suitable number of radiating blades having type x as shown diagrammatically in plan in Fig. 15; these blades 5 each have on their outer face one of the numbers or signs in question and on their lower face, in one part the corresponding printing type at y , at another part the perforating punch z . The machine effects simultaneously 10 the printing and the perforating of the sheet of paper, x' being the center of rotation and A the bill to be prepared.

It will be understood that the tabulated 15 lines, that is, the strips bearing the tabulated lines, are subsequently attached to the respective assemblage sheets at the controlling stations.

Having now particularly described and 20 ascertained the nature of my said invention and in what manner the same is to be performed, I declare that what I claim is:

1. In the art of manifolding tabulated statements, such as account sheets or way 25 bills, the process which consists in simultaneously perforating a plurality of superimposed sheets having the desired tabular rulings in correspondence to the numbers and signs indicated on the topmost sheet, 30 thereafter setting up the type and spaces in a line and in accordance with said perforations and rulings and so that they will respectively occupy the exact positions indicated by the horizontal position of the perforations and then printing such set up 35 line on each sheet.

2. In the art of manifolding tabulated statements, such as account sheets or way bills, the process which consists in simultaneously 40 perforating a plurality of superimposed sheets having the desired tabular

rulings in correspondence to the numbers and signs indicated on the topmost sheet, thereafter setting up the type and spaces in a line and in accordance with said perforations and rulings and so that they will respectively occupy the exact positions indicated by the horizontal positions of the perforations and then printing such set up line on each sheet, and finally attaching each tabulated line so made to the respective tabulated assemblage sheets. 50

3. In the art of manifolding tabulated statements, such as account sheets or way bills, the process which consists in simultaneously 55 perforating a plurality of superimposed sheets having the desired tabular rulings and printing the signs and numbers corresponding to the perforations on the topmost sheet, thereafter setting up the line 60 of signs and numbers properly spaced to correspond to the tabular rulings by passing the perforated portions of the sheet through a monotype machine, and thereafter printing said line on each sheet. 65

4. In the art of manifolding tabulated statements, such as account sheets or way bills, the process which consists in simultaneously 70 perforating a plurality of superimposed sheets having the desired tabular rulings and printing the signs and numbers corresponding to the perforations on the topmost sheet, thereafter setting up the line 75 of signs and numbers properly spaced to correspond to the tabular rulings by passing the perforated portions of the sheet through a monotype machine, and thereafter printing said line on each sheet, and finally attaching the tabulated lines so made to the respective assemblage sheets. 80

In testimony whereof I have signed this specification in the presence of two subscribing witnesses.

GUSTAVE PÉREIRE.
